DESIGN FOR A NOVELTY COIN BANK

Alfred L. Edgerle, Coffeyville, Kans.

Application November 15, 1944, Serial No. 116,336

Term of patent 3½ years

(Cl. D34—11)

To all whom it may concern:

Be it known that I, Alfred L. Edgerle, a citizen of the United States, residing at Coffeyville, in the county of Montgomery and State of Kansas, have invented a new, original, and ornamental Design for a Novelty Coin Bank, of which the following is a specification, reference being had to the accompanying drawing, forming a part thereof.

I claim:

The ornamental design for a novelty coin bank, as shown.

ALFRED L. EDGERLE.
